US0D1010236S

(12) United States Design Patent (10) Patent No.: US D1,010,236 S
(45) Date of Patent: * Jan. 2, 2024

(54) CONCAVE SIDED ANIMAL CARRIER

(71) Applicant: Katherine Blackshaw, Fayetteville, AR (US)

(72) Inventor: Katherine Blackshaw, Fayetteville, AR (US)

() Term: 15 Years

(21) Appl. No.: 29/856,007

(22) Filed: Oct. 10, 2022

Related U.S. Application Data

(63) Continuation-in-part of application No. 29/763,572, filed on Dec. 23, 2020.

(57) CLAIM

The ornamental design for a concave sided animal carrier, as shown and described.

DESCRIPTION

FIG. 1 is a perspective view of a concave sided animal carrier showing my new design;

FIG. 2 is another perspective view thereof;

FIG. 3 is another perspective view thereof;

FIG. 4 is another perspective view thereof;

FIG. 5 is a front view thereof;

FIG. 6 is a back view thereof;

FIG. 7 is a left side view thereof;

FIG. 8 is a right side view thereof;

FIG. 9 is a top view thereof; and,

FIG. 10 is a bottom view thereof.

The broken lines in the figures illustrate portions of the concave sided animal carrier that form no part of the claimed design.

1 Claim, 10 Drawing Sheets
